UNITED STATES PATENT OFFICE.

NELLIE MADSON, OF IROQUOIS, SOUTH DAKOTA.

DESIGN FOR A TOASTING-SPOON.

50,393.

Specification for Design.

Patented Feb. 27, 1917.

Application filed December 5, 1916. Serial No. 135,279. Term of patent 7 years.

To all whom it may concern:

Be it known that I, NELLIE MADSON, a citizen of the United States, residing at Iroquois, in the county of Kingsbury and State of South Dakota, have invented a new, original, and ornamental Design for Toasting-Spoons, of which the following is a specification, reference being had to the accompanying drawings, forming a part thereof.

Figure 1 is a plan view of the spoon showing my new design; and
Fig. 2 is a side elevation of the same.

I claim;

The ornamental design for a toasting spoon as shown.

NELLIE MADSON.

Witnesses:

E. O. COOPERSOHN,
FLORENCE BRIEDWELL.
